UNITED STATES PATENT OFFICE.

CHARLES E. DURYEA, OF READING, PENNSYLVANIA.

MAGNETIC IGNITER.

No. 872,503.

Specification of Letters Patent.

Patented Dec. 3, 1907.

Application filed September 14, 1906. Serial No. 334,675.

To all whom it may concern:

Be it known that I, CHARLES E. DURYEA, a citizen of the United States of America, and resident of Reading, in the county of Berks 5 and State of Pennsylvania, have invented certain new and useful Improvements in Magnetic Igniters, of which the following is a specification.

My invention consists of an igniting device 10 particularly adapted to internal combustion engines wherein the spark for igniting the explosive charge is produced by a magnetic igniter or spark plug adapted to the gas engine cylinder or cylinders and operated without 15 the use of mechanical parts attached to the engine other than a device for making and breaking the circuit at the proper time.

The objects of this invention are to provide a spark plug that will produce a spark of 20 the make and break variety with mechanism embodied in the plug itself so that by removing and exchanging plugs a good one may be substituted for a faulty one and the necessity of repairing, replacing or adjusting the 25 faulty one at an inconvenient time be avoided; to provide a means for varying the time at which the spark may occur with reference to the piston movement by varying the time of making and breaking the electric circuit 30 instead of varying the mechanical devices commonly used to produce the make and break spark; to insure the production of the spark absolutely at the proper time and without relation to the rate of vibration of 35 any spring or vibrating current breaker, as will be hereafter explained; to secure a large, hot, fat spark with a minimum expenditure of electric current and with a minimum likelihood of loss of current by faulty insulation 40 or by the fouling of the insulation; and other objects as will be set forth in this specification. I accomplish these objects by means of the device shown in the accompanying drawings forming part of this specification in 45 which.

Figure 1 is a plan view of the top of the plug. Fig. 2 is an elevation partly in section showing quite fully the construction of the plug. Fig. 3 is a detail bottom plan of the 50 end of the plug that projects to the engine cylinder. Fig. 4 is an enlarged section on the line 4—4 of Fig. 2. Figs. 5 and 6 show a modification. Fig. 7 is a view similar to Fig. 2 showing a slightly modified form.

Similar letters refer to similar parts throughout the several views.

The plug consists of a soft iron core *a* and a soft iron jacket *b* arranged to form an iron clad magnet closed at one end, preferably by screwing the core into the threaded end of 60 the jacket by which arrangement I secure ease of construction and the ability to remove the core and the parts it contains for inspection or repairs, without disturbing the jacket and the parts mounted upon it. See 65 Fig. 2. The space between the core and the jacket is filled with a bobbin or winding of magnet wire which may be insulated in the customary manner but is preferably insulated with something able to resist heat, such 70 as a mixture of water glass and powdered lava. I preferably fit this bobbin of wire tightly into the jacket and loosely upon the core, which permits the core to be removed without disturbing the wires. 75

One end of the wire is grounded upon and attached to the jacket *b* by soldering, riveting or other suitable means and the other end of the wire is attached to an insulated binding post *c* mounted upon the outer wall of 80 the jacket *b*, provision being made for the passage of the wire through the wall of the jacket *b* with ample insulation around it. The binding post *c* and a similar one *d* have thin metallic bases formed like part of a cylinder, which enables them to fit around the jacket *b*. They do not, however, meet each other as will be seen in Fig. 1 and they are insulated from the jacket *b* by a ring surrounded on each side by a layer of mica or 85 similar material. That they may be held in place without screws liable to penetrate the jacket, and possibly contact with the wire inside, another layer of insulating material is laid outside the flat bases of these posts and 90 a winding of wire *P* holds the bases and the two layers of insulating material firmly in place; a simple, satisfactory and permanent fastening. Of course, any other suitable fastening may be used. 100

On the insulated binding post *d* is pivoted an armature *e*. This armature is held out of contact with the magnet by a thin layer of suitable material or as we have shown, by an insulating material like mica and when not 105 under the influence of magnetism, due to a current passing through the wire of the magnet, a spring *f* lifts the armature some distance away from the poles of the magnet. This armature *e* has a small hole through its 110 center through which passes a reciprocating spark electrode rod *g*. This electrode rod is

long and slim, of light weight, and provided at its outer end with a head h' against the under side of which the armature contacts when not closely drawn to the magnet. On 5 the upper side of this head, the spring f bears very forcibly when the armature is down; but only slightly or not at all when the armature is up. A second spring h also bears lightly on this head, so as to insure that the 10 point of the electrode g' remains down and in contact with its complementary electrode i except when lifted and held out of contact by the armature e under the action of the spring f . When the armature is down nearly in 15 contact with the magnet the magnetic pull (varying substantially as the square of the distance) is quite strong, which insures a good contact between the spark electrodes g and i . This forcible pull also produces a 20 short bend in the spring f over the head of the electrode g and insures that when the current through the magnet is broken the armature is lifted quickly and forcibly, which coming in contact with the head of the electrode rod g , strikes it a hammer blow and knocks it out of contact with the electrode i in a manner calculated to produce a most 25 satisfactory spark if a current is flowing through the spark points at this time. 30 Neither spring offers much resistance to a rebound so both the armature and the electrode rod rise above their normal positions thus producing a wide gap after which they at once fall to their normal positions as determined by the spring f , the armature remaining some distance from the end of the magnet and the electrode g' remaining a short distance away from the point of the electrode i until current again passes through the coil 35 of the magnet. The electrode i is screw-threaded for purposes of adjustment. The electrode rod g reciprocates in a long tubular support o , which is provided near its upper end with a metallic flange and is guided and 40 held in position by mica washers surrounding the tubular portions on each side of the flange and clamped tightly in place by a nut p threaded into the upper end of the core a . By this arrangement the insulating material 45 is at a considerable distance from the heat, smoke, lubricating oil or similar causes of fouling likely to be found in the explosion chamber and therefore seldom needs cleaning. When it is necessary, however, to clean 50 this insulation, the jacket may be unscrewed from the core without disturbing the winding, the armature, the adjustment of the springs or the insulations of the binding post and by unscrewing the nut p , new insulations can be provided for the tubular support 55 o . The electrode rod g is of such small diameter and of such great length in the tubular support o that almost no leakage takes place, while this construction prevents clogging and 60 insures, as has been determined by usage,

that the electrode rod g shall remain free to move and not be likely to stick or move with difficulty or in any way interfere with the action of the device.

A diagrammatic arrangement of the parts 70 as arranged for use is shown in Fig. 2. The battery indicated at 4 has one wire grounded upon the engine. From the other pole wires are carried to the ordinary spark coil here- 75 fore described shown at 5 and also to the circuit breaker shown at 6. This circuit closer consists of an adjusting screw j and a movable or elastic contact piece k mounted upon an insulating base 1, which is journaled to swing around the shaft m . This shaft 80 carries the cam or equivalent device n adapted to bring the breaker k in contact with the screw j at proper intervals and also at the proper time disengage or permit the disengagement of this contact so as to break the 85 continuity of the electric circuit. From the screw j a wire leads to the binding post c of the spark plug shown in Fig. 2. From the coil 5 to the binding post d a wire also leads. By inspecting this diagram it will 90 be seen that a current may pass from the battery to the circuit closer when the circuit is closed, thence through the coil of the magnet to the jacket of the magnet, thence to the core of the magnet and plug, thence to the engine and thence through the ground wire to the battery. It will also be evident that when the armature e is drawn down by the magnet a second circuit will be completed from the battery to the coil from the 100 coil to the post d , from the post through the springs f and h to the electrode rod g , through this to the electrode i , the core of the plug and the engine and thence back to the battery. The action of the plug is therefore as follows:—When the shaft m in the course of 105 its movement or because of the shifting of the circuit closer around the shaft, causes the cam n to complete the circuit through the magnet of the plug by bringing the contact piece k into contact with the screw j , the magnet becomes saturated, attracts the armature e and closes the circuit through the electrode g' . This at once permits a flow 110 of current through the coil 5 and lessens the flow through the magnet but since the magnetic pull when the armature is close to the magnet, is very much greater than when at some distance, it will be readily understood that a very slight amount of current will 115 suffice to overcome the tension of the spring f and maintain the circuit through the coil 5 while the major portion of the current flowing through this coil fully saturates it, so as to insure a large spark when the circuit 120 through this coil is broken. When in the revolution of the crank shaft m , the cam n no longer holds the breaker k in contact with the screw j , the circuit, slight as it is, becomes broken; the magnet loses its hold on 125 130

the armature *e*, which is then suddenly thrown upward by the tension of the spring *f* and strikes the head of the electrode rod *g* a blow, knocking it out of contact with the electrode *i* and producing a spark at the points. During the slight instant of time between the breaking of the circuit and the release of the armature *e*,—a perceptible period required by the magnet to lose its saturation, although slight,—the entire current from the battery is permitted to flow through the coil 5, thus saturating it to its fullest before its circuit is broken by the release of the armature *e*. This arrangement secures the entire strength of the battery to act on the armature to cause it to move quickly when the circuit is closed by the circuit closer. This expenditure of current, however, lasts only so long as it is needed to produce its effect upon the armature and draw it down against the magnet. The current is then shifted by the closing of the circuit through the coil 5 and expends itself largely in saturating this coil as is required for the production of a large spark. The relative amounts of current that may pass through the coil and the magnet when both circuits are closed is determined, of course by the relative resistances of those circuits. The coil 5 is usually wound with a coarse wire surrounding a long core, whereas the magnet of the plug is wound with a much finer wire surrounding a comparatively much shorter core and of a shape adapted to give a strong pull on the armature capable of producing a quick, powerful action, with a slight amount of current, which quick and powerful pull permits the use of a stiff spring *f* and insures a quick acting device suitable for high speed engines.

By the use of a circuit closer equipped with a number of breaking devices arranged at suitable intervals around the shaft *m*, so that the cam *n* may connect them in proper succession; by connecting each breaker separately to its respective plug and proper post, and by connecting the coil 5 to the proper post of all the plugs, multiple cylinder engines can be operated as readily as the single arrangement shown. In this event a single source of electricity and a single coil serves all the plugs. The circuit closer is designed for and adapted to the number of cylinders to be ignited while the plugs are duplicates each of the other and can therefore be interchanged or removed for cleaning or repair without disturbing the others.

The electrode rod *g* is of such small size and weight that it may be made of material adapted to resist heat and corrosion due to the sparking, because the cost of such slight amount of material is not excessive. Being light, it may be moved more rapidly than is the case with most sparking devices, which adds to the speed of the plug. The spark-

ing point or electrode *i* is likewise small and can be made of good quality without much expense. This screw being adjustable, permits the adjustment of the plug as the points in contact wear away. By having the electrode *i* of substantially twice the diameter of the electrode rod *g* and slightly eccentric thereto, turning the screw electrode *i* both varies the distance between the points and brings a new contact surface on the end of the screw electrode *i* against the point of the electrode rod *g*; thus adding to the life of these parts. The electrode rod *g* can be readily removed by loosening the binding post *d* in a self-evident manner, so as to release the springs *f* and *h* sufficiently to permit them to be swung slightly to one side and permit the electrode rod *g* to be withdrawn from its support. In Figs. 1 and 2 the mica or other insulating material has not been lettered but has been indicated by the solid black used.

It will be noted that the insulation is far back from the opening into the engine, and said opening is small and any oil or soot passing through the opening can hardly reach the insulation. This soot may deposit, however, on the walls of the opening until it finally touches the needle and if this needle did not move the soot would make a short circuit, but since the needle is normally in motion it constantly breaks loose any particles of soot and prevents this effect. This is considered of great importance.

In my device a light current finds the spring *f* without tension and the armature *e* is therefore readily drawn toward the magnet until the electrode rod *g* is brought into contact with the electrode *i*. The spring *f* must then be strained over the head of the electrode rod *g* in order to permit further movement of the armature but since the armature is, at this time, so close to the magnet, even a slight current will overcome this strain and complete the travel of the armature. The value of this straining action is two-fold. The contact points are forced together with great pressure, thus absolutely insuring a contact between the sparking points in spite of soot or scale, which contact is necessary to be able to produce a spark and second the spring *f* being under great tension, quickly starts the mass of the armature away from the magnet and causes it to strike a sharp hammer blow on the electrode rod *g* while the rebound of the electrode rod and armature above their normal position quite perceptibly increases the length of the spark gap and facilitates ignition.

Not only is it desirable that a suitable spark as large as possible may be produced for starting, but it is also desirable that this spark shall be as large as possible when running. With devices in which the circuit is broken as soon as the magnetism reaches a

given strength, it is quite evident that the size of the spark will not appreciably increase with an increase in the strength of the current but that the increased current simply saturates the magnet more quickly up to the breaking point instead of more strongly. With my device a current that is strong enough to ignite will, if the wirings are properly proportionate, be strong enough to act upon the armature *e* and close the circuit through the coil 5, while, as in starting, the slow speed of the motor will permit this weak current to have ample time to fully saturate the coil before the circuit is broken and therefore permit the largest spark possible from the coil with the weak current. At higher speeds and with much stronger currents, the circuit through the coil 5 is closed more quickly and after closing the coil 5 is saturated proportionately to the strength of the current, so that when the points separate the spark is correspondingly larger. Another value in my device arises from the fact that although the length of contact at the circuit-closer 6 varies inversely as the speed of the engine, being greatest at slow speeds and least at high, the respective periods of time required by the magnet and the coil varies slightly so as to take advantage of the conditions under which they work. At slow speeds and with light current the magnet saturates slowly but because of the low speed, there is ample time to saturate the coil. With a large current the magnet saturates to the strength required more quickly, leaving a greater proportion of the period of contact for the saturation of the coil. On this account the length of contact at the circuit-closer 6 need be very little greater with this device than with a common make and break device of the mechanical kind.

While I prefer to employ a reciprocating pin for the production of the spark in connection with a magnet for closing the circuit through the coil, it is quite evident that other mechanical arrangements may be used instead of this.

While I have shown in Fig. 2 the binding posts held in position and insulated without the use of screws, because screws passing through the binding posts from the outside are likely to strike the insulated wire and do damage, I frequently use screws of special shape as seen in Figs. 5 and 6 having heads 11 inside fitted to slots 12 cut in the inner wall of the shell into which the screws sink flush and thus do not interfere with the winding while the screw head being rectangular in cross section as seen in Fig. 6 prevents the screw from turning when a nut 13 is applied on the outside. Fig. 5 shows an enlarged section of the shell with the slot and screw hole. The insulation *t* is also shown in Fig. 5.

While I have shown this device, as operated from a single source of current, it is a fact that a light current will suffice to operate the magnet, while a heavy current is better for the sparking circuit because a large spark is more effective than a small one as most automobilists know. I can, therefore, and frequently do, utilize a second source of current introduced as shown in Fig. 7, the wire *S* shown in Fig. 2 being not used in this instance. This additional source of current is indicated by the letter *w* in said Fig. 7. With this arrangement, it will be readily seen that when the circuit closer closes the magnet circuit, the magnet closes the sparking circuit and that each is absolutely independent of the other.

What I claim as new is:

1. In a magnetic igniter, a circuit breaker mechanism consisting of a reciprocating pin, 85 an electrode carried at one end thereof, an adjustable coacting electrode, an armature contacting said pin intermittently, a spring engaging said armature to move it in one direction, an independent spring of less power 90 mounted on the same support as the first-named spring and acting on said pin, and an insulated binding post.

2. In a magnetic igniter, multiple electric paths and suitable mechanism embodying a 95 movable part to carry the ignition current, a light spring, a heavy spring arranged to forcibly and elastically close the ignition circuit under the pull of an armature, but normally free, and an armature arranged to impart a 100 strong pull against the heavy spring.

3. In a magnetic igniter, multiple circuit paths, one an insulated path for an igniting current normally broken, and means for closing said path consisting of an electric magnet, a movable part to carry the ignition current, a light spring acting on said part, a heavy spring normally free but arranged to forcibly and elastically close the insulated path when attracted by the magnet coil 105 through the medium of an armature, and an armature arranged to impart a strong pull against the heavy spring.

4. In an igniting device, two electric paths and suitable means embodying a movable 115 part, a light spring acting thereon, a heavy spring normally free but arranged to forcibly and elastically close the circuit under the pull of an armature, and an armature arranged to impart a strong pull against the heavy 120 spring.

5. In an igniting device, a reciprocating circuit breaking rod carrying an electrode and supported by and carried in an insulated bushing or support, a light spring acting on 125 said rod, a heavy spring normally free but arranged to forcibly and elastically close the circuit under the pull of an armature, and an armature arranged to impart a strong pull against the heavy spring.

6. In combination with a magnetic igniter, a source of electric current, two electric circuits through the igniter and means embodying a movable part to carry the ignition current, a light spring acting thereon, a heavy spring arranged to forcibly and elastically close the ignition circuit, and coöperating means, whereby said ignition circuit is made and broken upon the closing of the other circuit.

7. In a magnetic igniter, a movable part arranged to carry the ignition current, a light spring arranged to move said part into closed circuit position, a heavy spring normally free but arranged to forcibly and elastically close the circuit under the pull of an armature, an armature arranged to impart a strong pull against the heavy spring, a magnet, and suitable binding posts.

8. In a magnetic igniter, a moving sparking part, an insulated support therefor, a removable core carrying said support, a light spring arranged to set on said moving part,

an independently movable heavy spring movable from the same center as the first-named spring and normally free but arranged to forcibly and elastically close the circuit, and means coöperating with said parts, as and for the purpose specified.

9. In an igniting device, multiple electric paths forming a magnet and an ignition circuit, electrodes one of which is movable, means to close the magnet circuit and attract its armature, a normally free spring arranged to forcibly and elastically bring the electrodes together and close the ignition circuit under the pull of said armature, and means for keeping said movable electrodes in contact with said spring.

Signed by me at Reading Penna. this 11th day of September 1906.
